(57) **CLAIM**

The ornamental design for a headboard pillow, as shown and described.

DESCRIPTION

FIG. 1 is a front perspective view of a headboard pillow, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing the headboard pillow in a state of use.

The broken lines of supporting rods in FIGS. 1 to 6 and 8 to 9 in the drawings illustrate the portions of the headboard pillow which form no part of the claimed design. The broken lines in a front side and a top side represent a first pattern of the headboard pillow and form no part of the claimed design. The broken lines in a left side and a right side represent a second pattern of the headboard pillow and form no part of the claimed design. The broken lines in class elliptical openings of the left side and the right side of FIG. 7 represent a sewing line of the headboard pillow and form no part of the claimed design. Additional broken lines in FIG. 9 in the form of a phone represent environment and form no part of the claimed design.
